US00D599775S

(12) **United States Design Patent**
Onoue

(10) **Patent No.:** **US D599,775 S**
(45) **Date of Patent:** **** Sep. 8, 2009**

(54) **RADIO COMMUNICATION DEVICE**

(75) Inventor: **Tsuyoshi Onoue**, Osaka (JP)

(73) Assignee: **ICOM Incorporated**, Osaka (JP)

(**) Term: **14 Years**

(21) Appl. No.: **29/272,566**

(22) Filed: **Feb. 12, 2007**

(30) **Foreign Application Priority Data**

Aug. 18, 2006 (JP) 2006-021916

(51) **LOC (9) Cl.** **14-03**

(52) **U.S. Cl.** **D14/188; D14/137**

(58) **Field of Classification Search** D14/137,

D14/155, 168, 169, 188, 192-198, 204, 217,

D14/257, 258, 265, 496; 455/344-351; 369/6-12

See application file for complete search history.

(57) **CLAIM**

The ornamental design for a radio communication device, as shown and described.

DESCRIPTION

FIG. 1 is a front view of a radio communication device in accordance with the present design;

FIG. 2 is a back view thereof;

FIG. 3 is a right view thereof;

FIG. 4 is a left view thereof;

FIG. 5 is a top view thereof;

FIG. 6 is a bottom view thereof; and,

FIG. 7 is a perspective view thereof.

The portions of the radio communication device shown in broken lines form no part of the claimed design.
